UNITED STATES PATENT OFFICE.

WILLIAM C. SCHEU, OF UPLAND, CALIFORNIA.

METHOD OF HEATING ORCHARDS AND APPARATUS THEREFOR.

Application filed July 14, 1923. Serial No. 651,667.

This invention relates to an improved method of heating orchards or crops of various kinds to protect them from damage by frost or lowering temperatures.

5 It has been the practice heretofore to accomplish this desirable result through the operation of a vast number of individual heaters distributed at spaced intervals throughout an orchard or other area containing growing crops.

These individual heaters have been of various types and description, the simplest being the well known smudge pot which attempts to accomplish protection to the trees or crops, more from a heavy smudge or smoke than from a liberation of heat from the burning fuel.

Another and more popular type of device is a heater designed to generate a gas from 20 a body of oil, and, through a proper mixture of air to form a combustible mixture and burn the same without smoke or smudge and thereby create quite an intense heat which radiates out around the trees or crops 25 and maintains a temperature above the frost or freezing point and thus protects them from damage.

This type of gas generating and gas burning heater has proven highly efficient in 30 practice and has become the standard type for general use.

The employment of this type of individual heater requires from fifty to eighty heaters per acre so that a twenty acre 35 orchard, for instance, would require in the neighborhood of one thousand to sixteen hundred individual heaters. This requires a number of assistants with torches to fire each heater whenever heat is required and 40 at the same time to adjust the air draft on each heater to suit the oil level in the bowl, more or less air being required according to the gas generating space between the cover and the top of the oil.

45 If the heaters are operated over an extended period, readjustment of the air intake is desirable to get best results, all of which means more or less inspection and attendance from sufficient operators to keep 50 the entire equipment in proper operating condition.

If the period of operation extends over a sufficient time to consume all of the oil in the heaters refilling becomes necessary, requiring tank wagons and the usual appliances connected therewith.

Another popular type of heater is one designed to burn a solid or semi-solid fuel such as coke, coal, or coal dust mixed with saw dust and oil and any other combustible 60 material. These also require more or less attendance for efficient operation, and require refilling at frequent intervals if burned over an extended period. As small a number as two thousand in operation at 65 one time requires quite an equipment of an efficient sort to handle the fuel required.

My improved method of heating orchards, or other growing crops as illustrated and described in this specification is intended to 70 obviate many of the special requirements connected with operating individual heaters and has for a principal object the provision of a centrally located gas generating station, a gas container, conduits leading from 75 said container to branch gas lines running out through the orchard, each of the branch lines having burners located at properly spaced intervals and in sufficient number to supply the necessary heat. The burners extend out from the branch lines in any desired direction, preferably from the bottom or under sides of the pipes so as to distribute the heat near the ground where the 80 coldest air accumulates.

By concentrating the generation of gas at a central point and thereafter distributing it through the conduits and branch lines throughout the orchard, conduces to a minimum of labor expense, since one man, or 90 two at the most could easily operate a gas generating plant of sufficient capacity to protect a considerable acreage.

A further advantage of my improved method of heating orchards resides in the 95 immense amount of increased radiating surface brought into play with only the one gas generating plant. By placing the burners underneath the line pipes the pipes will soon become heated and will then add their quota 100 of radiation to that of the burners and thus help materially in keeping the temperature in the orchard from falling below the danger point.

Another important advantage resides in 105 centralizing the production of the combustible gas and generating it at one place, in just one piece of apparatus, instead of generating gas in one thousand or more individual pieces of apparatus distributed 110 throughout the area to be protected. Where large orchards of several hundred acres are

to be protected a number of generating units would be used, each unit taking care of ten, twenty or more acres according to the capacity of the individual units employed. 5 For such an equipment a centrally located oil tank piped to the several unit stations would supply oil as needed, thus saving much of the labor and expense of attending the ordinary type of orchard heater.

10 With such objects in view, as well as other advantages which may be incident to the use of the improvements, the invention consists in the procedure, and in the parts and combinations thereof hereinafter set forth 15 and claimed, with the understanding that the several elements constituting the same may be varied in proportion and arrangement without departing from the nature of the invention.

20 In order to make the invention more clearly understood there are shown in the accompanying drawings means for carrying the same into practical effect, without limiting the improvements in their useful applications, to the particular construction which, for the purpose of explanation, have been made the subject of illustration.

The apparatus illustrating my improved method of heating and protecting growing 30 and ripening crops is only diagrammatic. Many of the actual details connected with the construction and operation are intentionally omitted as forming the subject matter of another application.

35 The apparatus in the main, while generally diagrammatic in character, is approximately correct in arrangement and location of parts and correctly illustrates the method forming the subject matter of this application.

40 Referring now to the drawings forming a part of this application, where like figures of reference indicate like parts in the several views:

Figure 1 is a diagrammatic plan illustrating on a reduced scale the general location 45 and arrangement of an apparatus capable of utilizing my improved method. A portion of an orchard is indicated with pipe lines and burner openings located at spaced intervals to properly distribute the heat developed from the burning gases.

Figure 2 is an elevation looking in the direction of the arrow "A" of Fig. 1 and 55 illustrates the main operating parts of the gas generating appliances and the storage tank and delivery system of said gases to the distributing pipe lines.

In order to show as simple an apparatus as possible I have utilized several of my 60 standard type of smokeless orchard heaters as gas generators and have connected the generating space directly with a storage tank.

The gas generators convert the oil in the 65 bowls to a gas in the same well known man-

ner as when operating as orchard heaters, but instead of having a combustion stack for consuming the gas as generated the combustion stack is replaced with an imperforate pipe leading to the storage tank so that 70 all of the gas generated by the generating fire in each bowl is conveyed directly to the storage tank, from which it is withdrawn for distribution and consumption throughout the orchard.

75 I have designated the gas generators by the numeral 1, and the storage tank or capacity by the numeral 2. The gas as generated and delivered to the storage tank is not combustible without an admixture 80 of air. Leading from the tank 2 is a pipe 3 equipped with an air inlet valve 4, the pipe 3 leading to a suction blower 5. The blower 5 is motor driven by a suitable motor as at 6. Leading from the blower 5 is a 85 delivery pipe 7 leading to the main branch line pipe 8. From the line pipe 8 extend burner line pipes 9 located at properly spaced intervals and having burner openings 10.

90 The burners 10 are shown as located on the underside of the line pipes 9 so that the flame is projected toward the ground. I have shown this as preferred location. It will be readily understood however, that the 95 burner openings may be placed in any radial location in relation to the axis of the pipes.

A row of small burners might entirely encircle the pipes at spaced intervals, or the 100 burner openings might assume a spiral path of location along each pipe. They may be placed in any relative positions that is thought to give best results, and may be made of any desired size. In any event it is desirable that the burners are numerous enough and large enough to produce a hot 105 roaring fire, since such a fire is necessary to radiate sufficient heat to maintain a temperature of 32° or thereabout around the trees when outside temperatures are around in the low twenties.

110 The operation of my improved method of heating orchards would proceed in approximately the following manner. The bowls of the gas generators 1 would be filled to a previously determined proper level 115 with a suitable fuel oil and the oil ignited through the air inlet openings in the covers. As soon as the generators are warmed and begin to produce a gas it will accumulate in the tank 2 and as soon as the tank has a sufficient supply the suction blower 5 can be started when the gas will be drawn from the tank and sent out through the lines to the burners. An operator with a torch proceeds from line to line and ignites the gas 120 issuing from the burner openings. As the suction blower is started the air inlet valve 4 is opened so that a proper mixture of air and gas is sent out through the lines. After 125 the burners are all going the pipes will 130

gradually become heated so that they will add their radiation to that of the fires and thus send out among the trees or other crops a constant blanket of warm air that effectually protects them from the lowering temperatures. After a system of this kind is once put into operation the continuing of the operation is extremely simple and free of labor or other expense. The gas generator bowls will hold about 8 or 10 gallons of oil and will burn some hours at full capacity, that is assuming that bowls of the kind shown are used. If special gas generating units are provided they can of course be made to hold any desired quantity of fuel oil. In either event the attendance necessary to operate a system such as is shown and which is sufficient for a small orchard, and the supplying of oil and adjustments to the air inlets in the generating units, is a small matter compared to attending several thousand individual heaters distributed throughout the same orchard.

The longer the system is operated at one time the more efficient it will become, because after all of the pipe lines become properly heated, where overground metallic pipes are used, somewhat less oil will be consumed to maintain a proper temperature in the orchard, and, since the filling and other attendance necessary to the operation of the system is so simple and easy, continuous operation of the apparatus over days at a time is possible, and, after once getting everything in proper working order the attendant can look after other matters and give only casual attention to the apparatus.

In the foregoing description I have referred particularly to conveying the generated gases through above ground metallic conduits or pipes. I have shown and described this means as one way of carrying out my method. Underground or over ground conduits of metal, concrete, tiling or any other suitable material may be used without departing from the nature of my invention.

Likewise I have shown and described a gas generating apparatus built up of ready to hand units, to illustrate the application of my improved method. I therefore wish it understood that any type of apparatus for generating a gas from a suitable gas producing material and having means for delivering said gas to a system of conduits extending throughout an orchard or other area to be heated, as coming within the scope and meaning of my claims hereto appended.

I also wish to point out that in using the terms "fuel oil" and other such expressions I do not refer to any particular type or kind of oil, in fact, I do not confine myself to oil as the only material from which to produce a suitable gas for this purpose. Any material from which a combustible gas can be

generated may be used in any desired manner and in any suitable apparatus.

I also wish to further point out that while I have shown a means of admitting air to the gas after it leaves the source of storage, this procedure is not the only way in which air may be combined with the gas to produce a combustible mixture. A combustible gas may be produced that has the air incorporated in its manufacture, or, the air may be supplied at any desired point along the line of conveyance.

With certain types of burners the pure gas may be delivered to the burner and air mixed therewith at the point of combustion in any well known manner. Also it is not necessary that a suction blower be used in just the manner I have indicated. With a suitably arranged and constructed storage system the pressure necessary to force the gas through the conduits may be applied in any of the ways now employed for forcing gas through a delivery system, operating with or without a blower.

I also wish to point out that I have indicated quite large cross-section conduits as running from the gas generating station out among the trees in the orchard. These large conduits are necessary to prevent undue condensation of the gases and the deposition of residue thereby. Small pipes carry so small a volume of gas that condensation is practically unavoidable, and wherever condensation occurs, residue and carbonaceous materials will be deposited and the pipes thereby clogged resulting in complete failure of the system at a most critical time. There will be some condensation in large conduits when the apparatus is first started, but on account of conveying a large column of hot gas through thin walled pipes they soon become heated to a point where condensation is very slight or completely eliminated, and on account of the large cross-sectional area of the pipes considerable condensation and deposition of residue may occur before the flow of gas would be unduly restricted.

It is also to be particularly noted that I am dealing with a condensable gas, in that the gaseous vapor produced by this method of heating orchards will remain a gas only so long as it is comparatively hot, and it will be impossible to utilize this method unless the conveying pipes are large enough to maintain the natural heat of the gas until it reaches the outermost burner stations. Small diameter pipes would permit the gas to cool and condense as fast as it flowed into them and it would never reach the extremities of a heating system on a cold night.

What I claim as new and desire to secure by Letters Patent is:

1. The method of making, distributing and burning a temporary gas for the pro-

tection of orchards against frost damage consisting in subjecting a fuel oil to heat to convert it into a temporary gas at a generating station, mixing air with said gas, conveying said gas to points in said orchard and retarding the reversion of said gas to its liquid condition while being conveyed, and emitting said mixed air and gas at burner stations in said orchard remote from said generating station, and burning said mixture at said points of emission in the orchard along said pipe lines.

2. An apparatus for producing a temporary gas for protecting orchards against frost damage, comprising means for subjecting a fuel oil to heat to thereby produce

a condensable gas, an enlarged capacity for receiving said gas, large diameter pipe lines leading from said capacity for conveying said gas throughout an orchard while retarding the reversion of said gas to its liquid state, means communicating with said large diameter pipe lines for supplying air to said gas to produce a combustible mixture, and burners distributed in said orchard along said pipe lines for burning said mixture at different points in the orchard as the mixture is conveyed through said pipes.

In testimony whereof I affix my signature.

WILLIAM C. SCHEU.
